CONDUIT CONSTRUCTION

Morton L. Spackman, Cleveland, Ohio, assignor
to The Ric-wil Company, Cleveland, Ohio,
a corporation of Ohio

Application August 12, 1931, Serial No. 556,630

14 Claims. (Cl. 137—75)

This invention relates to conduit construction and is particularly useful for use in conjunction with underground pipes such as are used in the transmission of steam, water and other fluid materials.

An object of the invention is to provide an improved construction which may conveniently be used with subterranean lines.

Another object is to provide an improved construction which will efficiently support underground pipes.

Another object is to provide an improved construction unit which may easily be formed of ceramic material.

Another object is to provide an improved construction unit which when made of ceramic material will be relatively free from deformation during manufacturing or firing.

Other objects will hereinafter appear.

This invention constitutes an improvement upon the inventions disclosed in the patent to Christian Gottwald, Number 1,681,731, issued August 21, 1928.

The invention will be better understood from the description of one practical embodiment thereof, illustrated in the accompanying drawing, in which:

Figure 1 is a cross-sectional view of a completed conduit system embodying the invention;

Figure 2 is a perspective view of a single unit or section of tile used in constructing the base drain of Figure 1;

Fig. 3 is a cross-sectional view of an older form of base drain and some associated parts, and

Figures 4 and 5 are, respectively, a perspective view and cross-sectional view of the base drain of Figures 1 and 2 with pipe supporting means positioned thereon.

As shown in Figures 1, 2, 4 and 5, the base drain consists of a row of hollow tiles, each having a flat bottom web or base 1, inwardly inclined sides 2, and a concave top 3. Upon the outer surfaces of the sides 2 are projections having their tops formed into substantially horizontal shoulders 4, while at the juncture of the sides with the top are formed bead-like ridges 5 by which the shell surrounding the fluid conveying pipe is supported.

The central portion of the tile is cut away, as indicated at 6 from about the level of the shoulders 4 upwardly, the space so provided being adapted to receive the bellied ends of the shell sections.

The shell or casing consists of cylindrical tiles split longitudinally into upper and lower halves 7

and 8, respectively, and provided adjacent the split portion with flanges 9 forming grooves for the reception of cement or other sealing material.

Centrally of the casing is arranged a steam or water pipe 10 supported upon brackets, as most clearly indicated in Figure 1. Each bracket consists of a transverse vertically arranged web 11 which may be placed between the upper ends of consecutive base drain tiles, this web being provided at its ends with flanges 12 parallel to the sides of the tile, and with horizontal flanges 13. The upper portion of the web 11 has formed upon it cradle-like bearing members 14 which support a roller 15 having trunnions 16 arranged to roll in notches 17 in the upper edges of the members 15. Web 11 extends through a hole in shell section 8.

The pipe 10 rests upon the rollers 15, and by them is supported so that it may slide slightly within the casing to allow for expansion and contraction.

Between the shell and pipe 10 is placed heat-insulating material which may be either a covering applied to the exterior of the pipe or to the interior of the shell, or a filling of more or less loosely associated material.

Heretofore the base drain tiles have been made as shown in Figure 3 having straight inclined sides 102 which were embraced by the flanges 12 and thus supported the roller carrying brackets. It will be obvious, particularly from Figure 3, that any variations in the width of a base drain would be reflected in a much greater variation in the height of the top of roller 15 from the bottom 101 of the base drain; also that the weight supported by the roller 15 was transmitted substantially normally to the sides 102, tending to collapse these sides and placing the flange 11 under a tensile strain. As this flange and its associated parts are most conveniently made of cast iron, this condition was extremely undesirable, as the cast iron is weakest in tension, and the hollow tile was subjected to forces which induced bending stresses in its sides.

It has therefore been necessary in some installations using the tile and base drain of Figure 3 to support flanges 13 upon concrete or the like, increasing the labor and expense in installing this system, and it has also at times been necessary to grind off flanges 12 and fit the supporting brackets to the base drain tiles to bring rollers 15 in alignment.

From Figures 4 and 5, it will be seen that with the improved form of this drain, flanges 13 rest on shoulders 4, so that the metal of the bracket

is under compression rather than tension and that the weight is transmitted through the shoulders and thickened portions of sides 2 to bottom 1, placing these sides under compression in the direction of their length and not tending to collapse the tile.

From Figure 5, it will be apparent that slight variations in the height of shoulder 4 from the bottom 1 are not magnified in the position of roller 15, but that this roller is raised or lowered by exactly the amount of such variations.

Another advantage of this form of base drain provided with shoulders is that the distribution of the clay or the like of which the tile is formed is substantially symmetrical with respect to a horizontal plane half way from the bottom of base 1 and the top of ribs 5. That is, the cross-sectional area of the clay above this plane is substantially equal to that below the plane. As these tiles are formed by being extruded through dies, this symmetrical distribution of material permits the extrusion of the material at a uniform rate at both the top and bottom of this section much more easily than with the sections illustrated in Figure 3. Moreover, when the older types of sections were fired, they exhibited a great tendency to bend and warp, as the top of the section, being smaller in extent, dried more quickly than the bottom, whereas with the improved tile, drying takes place substantially uniformly and distortion is greatly reduced. Probably the prevention of distortion is also aided by the strengthening imparted to the sides by the thickened portions forming the shoulders 4.

As the sides of the bracket do not have to engage the sides of the tile, liberal tolerances between tile and brackets may be allowed, so that variations in the width of either the tile or bracket will be provided for.

Moreover, the strengthening of the sides of the tile prevents the distortion of its ends. It is the practice to apply a board or the like to one end of a tile section as it leaves the die and then stand the tile on end upon the board, the tile remaining in this position during firing. Both the impact of the board and the weight of the tile tend to upset or expand the clay of the lower end, and these tendencies are to a large extent overcome by the increased strength of the sides.

While I have described the illustrated embodiment of my invention in some particularity, obviously many others will readily occur to those skilled in this art and I therefore do not limit myself to the precise details shown and described herein but claim as my invention all embodiments, modifications and variations coming within the scope of the appended claims.

I claim:

1. A base drain comprising a series of tiles each being an integral piece having two pairs of ribs, one pair along its top, and the other pair along its sides.

2. A one-piece tubular tile of substantially quadrilateral cross-section, one base being shorter than the other and the sides being thicker throughout a portion of their height than the bases, the upper edges of said thickened portion constituting supporting shoulders.

3. A one-piece tubular tile of substantially trapezoidal cross-section, the shorter base of which has two projecting parallel ribs and the sides of which have outwardly projecting ribs adjacent said base and tapering to adjacent the other base.

4. A one-piece tubular tile of substantially

trapezoidal cross-section, the shorter base of which has two projecting parallel ribs and the sides of which have outwardly projecting ribs adjacent said base and tapering to adjacent the other base, the tile being recessed for a portion of its extent, and the recess extending from the shorter base to said ribs upon the sides.

5

5. A one-piece tubular tile of substantially trapezoidal cross-section, the upper base of which is the shorter and has upwardly projecting parallel ribs, and the sides of which have upwardly projecting tapering ribs which are thickest adjacent the upper base.

10

6. A one-piece tubular tile of substantially trapezoidal cross-section, the upper base of which is the shorter and has upwardly projecting parallel ribs, and the sides of which have upwardly projecting tapering ribs which are thickest adjacent the upper base and terminate in substantially horizontal shoulders.

15

7. In combination, a series of hollow trapezoidal prismatic one-piece tiles open at the ends and arranged end to end, each tile having projecting ribs formed along its sides and provided with substantially horizontal surfaces, a plurality of supporting brackets each having feet resting upon said surfaces of two adjacent tiles, and a fluid conducting conduit supported by said brackets.

20

8. In combination, a series of hollow trapezoidal prismatic one-piece tiles open at the ends and arranged end to end, each tile having projecting ribs formed along its sides and provided with substantially horizontal surfaces, and ribs formed along its top, a plurality of supporting brackets each having feet resting upon said surfaces of two adjacent tiles, a fluid conducting conduit supported by said brackets, and a casing surrounding said conduit and supported by the ribs along the tops of the tiles.

30

9. In combination, a series of hollow trapezoidal prismatic one-piece tiles open at the ends and arranged end to end, each tile having projecting ribs formed along its sides, a plurality of brackets each positioned at the ends of successive tiles and having rigidly connected feet resting upon the upper surface of said ribs, supporting means associated with each bracket intermediate said feet, and a fluid conducting conduit carried by said supporting means.

40

10. In combination, a series of hollow trapezoidal prismatic one-piece tiles open at the ends and arranged end to end, each tile having projecting ribs formed along its sides, an integral bracket having feet resting upon the top surfaces of the ribs on opposite sides of the tiles, supporting means on said bracket intermediate said feet, and a conduit carried by said supporting means.

50

11. In combination, a series of hollow trapezoidal prismatic one-piece tiles open at the ends and arranged end to end, each tile having projecting ribs formed along its sides, an integral bracket having feet resting upon the top surfaces of the ribs on opposite sides of the tiles and supporting means intermediate said feet, a casing surrounding and supported directly on the tops of the tiles, and a conduit within said casing carried by said supporting means.

60

12. In combination, a series of hollow trapezoidal prismatic one-piece tiles open at the ends and arranged end to end, each tile having projecting ribs formed along its sides, an integral bracket having feet resting upon the top surfaces of the ribs on opposite sides of the tiles, the

70

85

75

75

feet being spaced apart slightly more than the width of the portion of the tiles between them, supporting means on said bracket intermediate said feet, and a conduit carried by said supporting means.

13. In combination, a series of hollow trapezoidal prismatic one-piece tiles open at the ends and arranged end to end, each tile having projecting ribs formed along its sides, an integral bracket having feet resting upon the top surfaces of the ribs on opposite sides of the tiles and loosely embracing the sides of the tiles, and supporting means intermediate said feet, a casing surrounding and supported directly on the tops

of the tiles, and a conduit within said casing carried by said supporting means.

14. In combination, a series of hollow trapezoidal prismatic one-piece tiles open at the ends and arranged end to end, each tile having projecting ribs formed along its sides, an integral bracket having feet resting upon the top surfaces of the ribs on opposite sides of the tiles, the feet being spaced apart slightly more than the width of the portion of the tiles between them, anti-friction supporting means on said bracket intermediate said feet, and a conduit carried by said supporting means.

MORTON L. SPACKMAN.
